PHASE CHANGER SWITCH

Edwin E. Wade, Charlottesville, Va.

Application March 8, 1948, Serial No. 13,549

1 Claim. (Cl. 200—6)

1

This invention relates to electrical equipment, and more particularly to a phase changer, by means of which it is possible to transpose the phases of an electrical circuit before they reach the load.

The primary object of the invention is to facilitate the changing of the phases of a three-phase electrical circuit.

The above and other objects may be attained by employing this invention which embodies among its features a pivot shaft, a pair of arcuate contacts supported in concentric spaced relation on opposite sides of the pivot shaft adjacent one end thereof, a pair of spaced contacts supported on each side of the pivot shaft adjacent the end remote from the arcuate contacts, a rocker supported midway of its ends on the pivot shaft to rock between the contacts adjacent opposite ends of the pivot shaft, a conductor bar at each end of the rocker, one end of each conductor bar continuously contacting one of the arcuate contacts, and the opposite end of each conductor bar being adapted selectively to contact one contact of each pair of contacts.

Other features include means manually to alter the position of the rocker and thereby selectively establish the flow of electrical current through the device.

In the drawings,

Figure 1 is a top plan view of a phase changer embodying the features of this invention,

Figure 2 is a longitudinal sectional view taken substantially along the line 2—2 of Figure 1,

Figure 3 is a vertical sectional view taken substantially along the line 3—3 of Figure 1,

Figure 4 is a sectional view taken substantially along the line 4—4 of Figure 3,

Figure 5 is a perspective view of one of the arcuate contacts,

Figure 6 is a perspective view of one of the resilient spaced contacts, and

Figure 7 is a diagram illustrating this phase changer in a conventional electrical circuit.

Referring to the drawings in detail, this phase changer embodies a base 10 from one face of which projects spaced parallel side walls 12 and 14. The base 10 and side walls 12 and 14 are preferably constructed of a suitable non-conducting material, and the side walls are provided with aligned openings for the reception of a conductor bar 16 for the neutral phase of a three-phase electrical system. Opposite ends of the conductor bar 16 are provided with conventional couplings 18 by which conventional conductors may be coupled to the bar. Extending transversely

2

between the side walls 12 and 14, in spaced parallel relation to the conductor bar 16, is a pivot shaft 20 upon which the rocker, to be more fully hereinafter described, is mounted.

Carried in suitable arcuate grooves 22 formed in the inner face of the wall 14 in concentric spaced relation to the pivot shaft 20 are arcuate conductors 24 and 26, each of which is provided with a conventional binding post 28 to which the conductors, to be more fully hereinafter described, are connected. As illustrated in Figures 3 and 4, the arcuate contact bars 24 are located on opposite sides of the pivot shaft 20, and their inner faces are exposed for engagement by the conductor bars of the rocker, as will be more fully hereinafter explained.

Fitted in suitable recesses 30 formed in the side wall 12 and opening through the inner face thereof are pairs of spring contacts 32 and 34, each of which is provided with a binding post 36 which extends through the wall 12 and is provided with a conventional coupling 38 by means of which the conductors, to be more fully hereinafter described, are connected to the contacts.

As illustrated, the contacts 32 are located on one side of the shaft 20 directly opposite the inner ends of the arcuate contacts 24 and 26, while the contacts 34 are located on the opposite side of the shaft 20 and opposite the outer ends of the arcuate contacts 24 and 26. The contacts 32 are connected by a conductor 38 to form one pair of contacts and the contacts 34 are coupled by a conductor 40 to form the opposite pair of contacts.

Mounted for rocking movement on the shaft 20 adjacent opposite side walls 12 and 14 are rock arms 42. As illustrated, these rock arms are mounted midway between opposite ends on the shaft 20, and extending transversely between the ends of the rock arms are conductor bars 44 and 46. As illustrated in Figure 3, the conductor bars extend through the rock arms 42, which are preferably formed of non-conducting material, and one end of the conductor bar 44 remains in constant contact with the arcuate contact 24, while the conductor bar 46 has one end in continuous contact with the arcuate contact 26. These bars together with the rock arms 42 form a rocker unit designated generally 48, and the ends of the bars 44 and 46 opposite those which engage the arcuate contacts 24 and 26 are adapted alternately to be moved into engagement with the contacts 32 and 34. It will be understood that when the conductor bar 46 engages the lower contact 34 of the pair of contacts nearer the end

while the phase 2 of the power line will communicate with the load through the lower contact 32, conductor bar 46, arcuate contact 26, and conductor 70 to the load. In this way, by the simple shifting of the rocker 48 from the full to the dotted line positions illustrated in Figure 2, the phases fed to the load from the power line may be altered at will.

While in the foregoing there has been shown and described the preferred embodiment of this invention, it is to be understood that minor changes in the details of construction, combination and arrangement of parts may be resorted to without departing from the spirit and scope of the invention as claimed.

Having described the invention, what is claimed as new is:

A phase changer comprising a base, a pair of spaced parallel side walls of non-conducting material carried by the base, a pivot shaft carried by and extending between said side walls, a pair of arcuate contact bars mounted on the inner face of one of the side walls in concentric spaced relation to the pivot shaft, two pairs of spaced contacts on the inner face of the opposite side wall disposed in concentric spaced relation about the pivot shaft, a rocker mounted intermediate its ends on the pivot shaft, a conductor bar carried by the rocker adjacent each end thereof, said conductor bars lying in spaced parallel relation to the pivot shaft, one end of the conductor bar at one end of the rocker continuously contacting one arcuate contact bar, one end of the conductor bar at the opposite end of the rocker continuously contacting the other arcuate contact bar, the ends of the conductor bars remote from the arcuate contact bars selectively contacting one contact of each pair of spaced contacts, and a plunger rod slidably mounted on the base and having one end coupled to the rocker manually to alter the position of the rocker.
